(57) **CLAIM**

The ornamental design for a battery cover, as shown and described.

DESCRIPTION

FIG. 1 shows a top perspective view of a battery cover in an unassembled configuration.

FIG. 2 shows a top plan view of the battery cover in the unassembled configuration.

FIG. 3 shows a bottom plan view of the battery cover in the unassembled configuration.

FIG. 4 shows a front elevation view of the battery cover in the unassembled configuration.

FIG. 5 shows a back elevation view of the battery cover in the unassembled configuration.

FIG. 6 shows a right elevation view of the battery cover in the unassembled configuration.

FIG. 7 shows a left elevation view of the battery cover in the unassembled configuration.

FIG. 8 shows a top perspective view of the battery cover in an assembled configuration; and,

FIG. 9 shows a bottom perspective view of the battery cover in the assembled configuration.

1 Claim, 7 Drawing Sheets
